Primary Examiner — Janice Seeger

(57) **CLAIM**

We claim the ornamental design for a table, as shown and described.

DESCRIPTION

FIG. 1 is a front perspective view of a table according to one embodiment;

FIG. 2 is a bottom perspective view of a table of FIG. 1;
FIG. 3 is a front view of a table of FIG. 1, the rear view is a mirror image of the front view of FIG. 3;

FIG. 4 is a left side view of a table of FIG. 1, the right side view is a mirror image of the left side view of FIG. 4.

FIG. 5 is a top view of a table of FIG. 1;

FIG. 6 is a bottom view of a table of FIG. 1;

FIG. 7 is a front perspective view of a table according to an alternate embodiment;

FIG. 8 is a bottom perspective view of a table of FIG. 7;

FIG. 9 is a front view of a table of FIG. 7, the rear view is a mirror image of the front view of FIG. 9;

FIG. 10 is a left side view of a table of FIG. 7, the right side view is a mirror image of the left side view of FIG. 10;

FIG. 11 is a top view of a table of FIG. 7; and,

FIG. 12 is a bottom view of a table of FIG. 7.

The dashed lines and broken lines are for purposes of illustrating environmental structure and form no part of the claimed design.
